UNITED STATES PATENT OFFICE.

ALEXANDER P. MOORE, OF CHICAGO, ILLINOIS.

DESIGN FOR A BOTTLE.

SPECIFICATION forming part of Design No. 19,640, dated February 11, 1890.

Application filed December 23, 1889. Serial No. 334,792. Term of patent 14 years.

To all whom it may concern:

Be it known that I, ALEXANDER P. MOORE, a citizen of the United States, residing at Chicago, in the county of Cook and State of Illinois, have invented and produced a new and original Design for a Bottle; and I do hereby declare the following to be a full, clear, and exact description of the same, reference being had to the accompanying drawings, forming a part thereof, in which—

Figure 1 is a perspective view of a bottle embodying my design, and Fig. 2 a vertical section thereof.

The leading feature of my design consists in a bottle the body of which represents a bale of cotton, having a rectangular panel on its face.

Referring to the accompanying drawings,

A designates the body of the bottle, which, as shown, represents a bale of cotton surrounded by any desired number of tie-bands B, and rising centrally from top of said bale is the neck of the bottle C. On the faces of the bottle is embossed a rectangular label provided at its outer edge with a raised portion D, and upon the face of said label may be embossed any suitable inscription.

What I claim is—

The design for a bottle herein shown and described.

In testimony whereof I affix my signature in presence of two witnesses.

ALEXANDER P. MOORE.

Witnesses:

C. MERRITT,
M. E. BEAN.
